UNITED STATES PATENT OFFICE.

WILLIAM B. GILES, OF NEW YORK, N. Y.

DESIGN FOR A GAME-BOARD.

SPECIFICATION forming part of Design No. 29,115, dated July 26, 1898.

Application filed June 16, 1898. Serial No. 683,622. Term of patent 3½ years.

To all whom it may concern:

Be it known that I, WILLIAM B. GILES, of the city of New York, borough of Manhattan, in the county of New York and State of New York, have invented and produced a new and original Design for a Game-Board, of which the following is a specification, reference being had to the accompanying drawing, forming a part thereof, which is a plan view of a game-board, showing my design.

The leading or material feature of my design consists in the surface of the board having two equal parts or fields with a groundwork of contrasting colors and having in each part or field a series of disk-like figures, the color of one series of disk-like figures differing from that of the other series.

Referring to the drawing, the parts or fields are represented by 1 and 2, the field 1 being

shown as light in color and the field 2 as dark. 20
In the field 1 is a series of disk-like figures, and in the field 2 is a series of disk-like figures. The figures in field 1 contrast in color with those in field 2. The disk-like figures are each surrounded by a circular border of 25 a color darker than that of the fields and disk-like figures, and these circular or ring-like borders form the outlines of substantially diamond-shaped figures between the disk-like figures. 30

I claim—

The design for a game-board, substantially as herein shown and described.

WILLIAM B. GILES.
